SWIMMING POOL

Robert M. Vance, Desert Ventures, Box 6226,
Tucson, Ariz.

Filed Apr. 10, 1964, Ser. No. 79,440

Term of patent 14 years

(Cl. D13—1)

Fig. 4.

Fig. 5.

Fig. 6.

Fig. 7.

Fig. 11.

Fig. 12.

Fig. 13

FIGURE 1 is a top plan view of a swimming pool showing my new design;

FIGURE 2 is a bottom plan view thereof;

FIGURE 3 is a side elevational view thereof;

FIGURE 4 is an end elevational view thereof;

FIGURE 5 is a transverse sectional view taken on the line 5-5 of FIGURE 1;

FIGURE 6 is a longitudinal sectional view taken on the line 6-6 of FIGURE 1;

FIGURE 7 is a perspective view thereof;

FIGURE 8 is a top plan view of a first modification of the swimming pool of FIGURES 1-7;

FIGURES 9 and 10 are sectional views taken on the lines 9-9 and 10-10, respectively, of FIGURE 8;

FIGURE 11 is a top plan view of a second modification;

FIGURES 12 and 13 are sectional views taken on the lines 12-12 and 13-13, respectively, of FIGURE 11.

This application is a continuation-in-part application of application Serial No. D. 74,899, filed May 15, 1963, now abandoned.

I claim:

The ornamental design for a swimming pool, substantially as shown and described.
